(57) **CLAIM**

The ornamental design for a dog toy, as shown and described.

DESCRIPTION

U.S. Pat. No. Des. 579,157—Dog Toy

U.S. Pat. No. Des. 774,710—Dog Toy

U.S. Pat. No. 6,360,693—Animal Toy

U.S. Pat. No. 8,225,747—Treat Dispenser for Animals and Method

U.S. Pat. No. Des. 407,868—Dog chew toy

US20070289553—Treat dispenser for animals

U.S. Pat. No. 6,941,895—Treat dispensing chew toy

U.S. Pat. No. Des. 587,862—Pet Toy

FIG. 1 is a perspective view of a dog toy showing my new design.

FIG. 2 is a top perspective view thereof.

FIG. 3 is a right side elevational view thereof.

FIG. 4 is a left side elevational view thereof; and,

FIG. 5 is a top plan view thereof.

The broken line showing is for the purpose of illustrating portions of the dog toy and forms no part of the claimed design.
